UNITED STATES PATENT OFFICE

111,249

DESIGN FOR A CABINET OR SIMILAR CONTAINER FOR LUBRICANTS

Alexander P. Fox, University City, Mo., assignor to Lincoln Engineering Company, St. Louis, Mo., a corporation of Missouri

Application January 10, 1938, Serial No. 74,185

Term of patent 7 years

To all whom it may concern:

Be it known that I, Alexander P. Fox, a citizen of the United States and a resident of University City, St. Louis County, Missouri, have invented a new, original, and ornamental Design for a Cabinet or Similar Container for Lubricants, of which the following is a specification, reference being had to the accompanying drawing, forming part thereof, in which

Fig. 1 is a side elevation of a cabinet or similar container for lubricants, showing my new design;

Fig. 2 is a front elevation thereof; and,

Fig. 3 is a perspective view thereof on an enlarged scale.

The sides of the cabinet or container opposite to those shown in the several figures are substantially the same in appearance. The characteristic features of my design consist in the parts shown in solid lines.

I claim:

The ornamental design for a cabinet or similar container for lubricants, substantially as shown and described.

ALEXANDER P. FOX.
